UNITED STATES PATENT OFFICE.

REUBEN COIL NELSON, OF HEALDSBURG, CALIFORNIA.

OIL-BURNER.

No. 888,644.

Specification of Letters Patent.

Patented May 26, 1908.

Application filed November 6, 1906. Serial No. 342,250.

To all whom it may concern:

Be it known that I, REUBEN COIL NELSON, a citizen of the United States, residing at Healdsburg, in the county of Sonoma and State of California, have invented a new and useful Oil-Burner, of which the following is a specification.

This invention has relation to oil burners and it consists in the novel construction and arrangement of its parts as hereinafter shown and described.

The object of the invention is to provide a hydro-carbon burner of the steam injector type said burner having a steam spraying means.

The burner consists primarily of a casing to which is connected an oil supply pipe, said casing is provided with a nozzle which in turn is provided with a steam spraying means.

A reducer is detachably or removably located within the casing. A valve cylinder is adjustably located within the casing and is provided with a reciprocating needle valve. The said adjustable valve casing and reducer coöperate with each other to control the suction power of the volume of steam passing through the casing. By such suction power the liquid fuel is drawn into the casing and mixes with the steam and the resultant mixture is sprayed from the end of the nozzle. External means is provided for adjusting the valve cylinder longitudinally within the casing. The said casing is provided with a steam inlet which is located behind the oil inlet and the said valve cylinder is provided with a steam admission port.

In the accompanying drawing:—the figure is a vertical sectional view of the burner.

The burner comprises the casing 1 to which is connected the steam pipe 2 and the oil pipe 3. The said oil pipe being connected with the casing 1 in advance of the said steam pipe. The casing is provided with the mixture outlet 4 to which is connected the discharge nozzle 5. The casing is also provided with the valve cylinder receiving portion 6. The reducer 7 is screw threaded in the discharge 4 and is provided with an oil admission port 8. The said reducer 7 is perforated longitudinally and is provided with the annular concaved surface 9 and the cylindrical portion 9' which extends over the oil pipe 3 and abuts at its end against the partition 1' provided in the interior of the casing 1. The port 8 is located in the cylindrical portion 9'.

The valve cylinder 10 is screw threaded in the receiving portion 6 of the casing 1 and passes through the partition 1' and fits snugly within the cylindrical portion 9' of 60 the reducer 7. Said cylinder 10 is adapted to move longitudinally in said cylindrical portion of the reducer 7 and increase or diminish the open area of the port 8. The stuffing box 11 surrounds the cylinder 10 and 65 slides with relation to the portion 6. The square or octagonal nut 12 is fixed to the cylinder 10 at a point beyond the end of the portion 6 of the casing 1. The stem 13 of the needle valve 14 passes longitudinally 70 through the valve cylinder 10 and the latter is provided with a thread 15 which engages the corresponding internal thread in the portion 6 and affords means for moving the said stem longitudinally.

The stuffing box 16 surrounds the valve stem 13 and is arranged to slide longitudinally of the valve cylinder 10. The outer end of the stem 13 is provided with the turning knob 17. The needle valve 14 is adapted 80 to engage or seat upon the surface of the reduced end 18 of the valve casing 10. The said reduced end 18 of the valve casing 10 is located within the reducer 7 and the needle point of the valve 14 projects into the most 85 contracted portion of the reducer 7. The valve casing 10 is provided with the steam admission port 19 which is located below or in alinement with the steam admission pipe 2. The nozzle 5 is provided with a discharge 90 outlet 20 and the steam passage 21 which has an outlet directly under the discharge outlet 20 and disposed in the same direction. The steam pipe 22 is connected with the steam passage 21.

The operation of the burner is as follows:—The needle valve 14 is closed against its seat. Steam is admitted through the pipe 2 into the casing 1 from whence it passes to the port 19 into the cylinder 10. The needle valve 14 is 100 then moved slightly from its seat and the steam escapes from the cylinder 10 and passes into the reducer 7 from which point it passes through the discharge 4, nozzle 5 and discharge outlet 20. In rushing by the 105 oil admission port 8 suction is created which draws the liquid fuel up through the pipe 3. The valve 23 having previously been opened, the oil passes through the admission port 8 and mingles with the steam and is thoroughly mixed therewith. This mixture is 110 expelled through the discharge outlet 20 of

the nozzle 5 where it is ignited. When it is desired to intensify the flame or force the draft, steam is permitted to pass through pipe 22 and passage 21 and thus the mixture 5 is sprayed as it comes from the discharge outlet 20 of the nozzle 5. The needle valve 14 may be opened to such a degree as to regulate the volume of steam injected to a nicety. The greater the volume of steam the greater will 10 be the suction produced and the volume of oil will correspond. Should it be desired to increase or decrease the quantity of the mixture the reducer 7 may be removed and one of a different capacity substituted in its 15 stead. Then by turning the valve cylinder 10 the said cylinder will be moved longitudinally back or forth according to the direction in which it is turned in order that the space between its inner end and the most contract- 20 ed portion of the reducer may be regulated to a nicety. Thus, the space within which the mixing of the two elements takes place may be increased or diminished at will to meet any requirement. 25 Having described my invention what I claim as new and desire to secure by Letters-Patent is:—
In an oil burner, a casing having an oil in-

let, and steam inlet separated by a partition, a reducer located in the casing, and having a 30 cylindrical portion extending over the oil inlet, and abutting against the partition of the casing, and provided with an oil inlet port; a valve cylinder projecting into the casing, with its forward end fitting snugly into the 35 cylindrical portion of the reducer, and adjustable therein, to enlarge, or diminish the opening of the oil inlet port of the reducer, said valve cylinder having a steam inlet port; and an adjustable valve controlling the discharge 40 of steam from said valve cylinder into the reducer; in combination with a discharge nozzle having a constricted outlet, for the discharge of oil and steam, and a steam passage disposed externally of the nozzle, and 45 connected with the steam supply pipe, and having a constricted outlet parallel with that of the nozzle, as herein set forth.

In testimony that I claim the foregoing as my own, I have hereunto affixed my signature in the presence of two witnesses.

REUBEN COIL NELSON.
